UNITED STATES PATENT OFFICE.

FRANK L. O. WADESWORTE, OF PITTSBURGH, PENNSYLVANIA.

FLUID-ACTUATED RECIPROCATORY DEVICE.

Application filed March 27, 1920. Serial No. 369,389.

This invention relates, generally, to the construction and mode of operation of fluid-pressure-actuated mechanisms of various types, and it is particularly adapted for use in air driven percussion tools, such, for example, as impact drills and pneumatic hammers or riveters which comprise a cylinder having therein a free piston member that is reciprocated at a high speed to deliver a rapid series of blows against another relatively stationary member (such as a drill stem or rivet set) located at one end of the cylinder.

The general objects of my invention are to greatly improve the operative design and the working performance of tools of this character; and to these ends my improvements are directed to the provision of a light, strong and powerful mechanism that can be readily used in any position, and to the more effective and efficient utilization of the working fluid, so as to not only increase the speed of action and the driving power of the tool, but also decrease its consumption of working fluid per unit of power developed.

More specifically stated, my invention is designed to provide a pneumatic hammer of minimum weight and size, which can be readily carried from place to place, and used with a minimum amount of fatigue by the operator, and which will have a maximum effectiveness both in increasing the force and the rapidity of piston impact against the rivet set (or other tool element) and also in decreasing the recoil or rebound action which tends to diminish the effectiveness of the blow, and which is also capable of being actuated with a less amount of working fluid than is required for other hammers of the same rated capacity. The advantages of these features of my improvements are very important because they enable the users of these tools to greatly increase their output; and also because they considerably reduce the expense of the operation and maintenance both of the hammers themselves and of the power plant that supplies the motive fluid thereto.

Other objects and advantages of my invention will be made apparent to those skilled in the art by the following explanation of certain embodiments of my improvements which are presented as generically illustrative of the manner in which the said improvements may be utilized in the various

types and forms of fluid actuated tools—the particular exemplary embodiment herein shown and described being a pneumatic hammer of the form now commonly employed in riveting and similar operations.

In carrying out my invention, I employ a cylinder having a reciprocatory piston therein and having suitable means for supplying motive fluid to the cylinder to actuate the piston. The cylinder is provided with inlet and exhaust ports at both ends and a control valve is provided for governing the admission and exhaust of fluid pressure to and from the piston chamber. The piston is moved on its power stroke by the direct action of the live motive fluid flowing into the cylinder from the main supply reservoir and in the practice of my invention a portion of the charge of live motive fluid, which actuates the piston on its power stroke, is segregated in a separate chamber and utilized for returning the piston on its reverse stroke this being, as I believe, a broadly new method or manner of actuating the reciprocating piston member.

As hereinbefore suggested my invention is peculiarly advantageous in connection with riveting hammers and like tools which are usually actuated by compressed air, and the invention is especially, though not essentially, adapted for application to a pneumatic riveting hammer of the "long stroke" type, in which the piston reciprocates a distance greater than its own length. In such tools the return of the piston has heretofore been effected by the admission of a fresh charge of live motive fluid from the main supply reservoir and the result of the action thereof on the piston was to gradually accelerate its speed during its return stroke, so that the maximum velocity was attained at the end of such stroke; and a severe shock was produced by the stoppage and reversal of the movement at the rear end of the piston chamber.

My method of operation differs from that just described in that, instead of admitting a fresh charge of live motive fluid for operating the piston on the return stroke, I utilize, for this purpose, the expansion of a segregated portion of the same charge of motive fluid that actuates the piston on its power stroke. The result of this is that the return movement is more promptly initiated, but the velocity of this movement is gradually decreased and is lowest when the

piston reaches the rear end of the piston chamber. Under such conditions the shock of reversal at the termination of said movement is greatly reduced.

5 The use of a single charge of live motive fluid to move the piston both on its power and return strokes also effects a considerable saving in live motive fluid without diminishing the power developed on the working 10 stroke and without sacrificing any of the advantages incident to the old mode of operation.

The accompanying drawings illustrate several specific forms of pneumatic hammer 15 constructions each of which constitutes an exemplification of my generic invention. In these drawings:

Figure 1 is a longitudinal sectional view through one form of tool embodying my 20 present improvements.

Fig. 2 is an enlarged sectional view of a part of the construction shown in Fig. 1 but showing the fluid control valve in another position.

25 Fig. 3 is a transverse section taken on the plane of line 3—3 of Fig. 1 as viewed in the direction of the arrows.

Fig. 4 is an enlarged sectional detail view 30 of a portion of the inner cylinder showing one form of check valve which is used in certain applications of my invention.

Fig. 5 is a perspective view of the said 35 check valve member.

Fig. 6 is a longitudinal sectional view 40 through another form of pneumatic hammer that also embodies the general features of my present improvements.

Fig. 7 is an enlarged sectional view showing the fluid control valve of this second 45 construction in position to effect the return stroke of the piston.

Fig. 8 is a detail view showing another 50 form of fluid check valve that is employed in the organization depicted in Figs. 7 and 8, and

Fig. 9 is a longitudinal section through 55 the front end of still another tool which embodies my invention.

Fig. 10 is a fragmental longitudinal sectional view through the front end of still 60 another tool, which embodies my invention.

In the construction shown in Figs. 1 to 5 the body of the tool is composed of outer and inner tubular members 10 and 11, with 65 in the inner one of which the piston 12 reciprocates. At the forward end of the tool is a rivet set bearing sleeve or holder 13 which is secured to the outer tube 10 and supports one end of the inner tube 11, and which is 70 adapted to receive the shank of a suitable rivet set 14 against which the piston is arranged to abut on its forward or power stroke.

At the opposite end of the tool is a handle 65 15 which has a tubular head or sleeve 16

that is screwed over the rear end of the body portion of the tool and is locked in place thereon by any suitable means, such as a ratchet ring 17, that engages with ratchet teeth on the end of the sleeve 16, 70 and is held from turning by the eccentric head of an adjustable (rotatable) deg or pin 17^a. Any suitable form of retainer, such as an annular spring clip 18 may be utilized to secure the parts 17 and 17^a in place; and 75 in the particular construction under consideration this clip 18 also serves as a guard ring or deflector for controlling and directing the escape of the exhaust from the piston chamber.

The rear end of the outer tubular member 10 is bored out to receive a two-part valve box which consists of a front section 19^a that engages the rear end of the inner tube 11, and a complementary section 19^b which engages the section 19^a and projects rearwardly into the recess in the handle head. These complementary sections 19^a—19^b are bored and finished to receive a reciprocatory valve member 20 of tubular or annular form, which is provided with three projecting ribs or flanges 29, 30 and 31, and which is adapted to control the openings of certain inlet and exhaust ports, and thereby govern the admission and escape of motive fluid, in a manner which will be presently explained. In the present instance the rear end of the inner tube 11 is supported by the front end of the valve box 19 and terminates in front of the valve member 20, but said tube may, if desired, be continued through the valve box member to the rear end of the piston chamber.

The space 21 between the outer and inner tubes 10 and 11 (the ends of which space are closed respectively by the rivet set bearing member 13 and the valve box section 19^a) constitutes a storage chamber which is adapted to receive and segregate a portion of the live charge of motive fluid that passes from the interior of the inner cylinder through ports 22 in the wall thereof, when the said ports are uncovered by the forward movement of the piston. These ports may be controlled by a check valve 23 that allows 115 an outward flow of the motive fluid from the piston chamber into the chamber 21 but prevents a reverse flow from the said chamber inwardly.

The exemplary check valve 23 shown in 120 the Figs. 1, 3, 4 and 5 is in the form of an annular band, of arched cross section, which is seated in a groove 24 in the inner tube 11 and which is divided or split, as at 25, to give greater circumferential resiliency and enable it to be readily sprung into place in the groove 24. Preferably the band is also provided with a series of open end slots 26 in its edges to increase its transverse resiliency and permit it to yield easily to the 125 130

outward pressure of the motive fluid in the piston chamber. Any suitable means—such as a pin 27 fixed in the tube 11 and entering an aperture 28 in the band—may be used 5 to secure this valve against accidental displacement.

The handle 15 is provided with a supply 10 passage 32 which is controlled by a valve 33 operated by a thumb lever 34 in the usual manner. The inner end of this passage 15 opens into the annular chamber 35 which surrounds the rear portion of the valve box 19. This chamber is in constant communication—through one or more small ports 36—with the annular chamber 37 in which the flange 29, of the valve 20, reciprocates. The wall of the valve 20 is provided with a suitable number of small ports 38 which are located just back of the valve flange 29, 20 and which serve the purpose of venting the chamber 37 and prevent the trapping of air therein when the valve member shifts rearwardly.

Another series of larger ports 39 extend 25 through the valve box and serve to deliver live motive fluid into the interior of the piston chamber when the main control valve 20 is in its forward position, as shown in Fig. 2, these ports being cut off by the valve 30 member 20 when in its rearmost position, shown in Fig. 1.

The forward end of the annular chamber 21 is in communication with the front end of the piston chamber through a circumferential row of radial ports 40; and the rear end of this chamber is connected—by one or more longitudinal passages 41—with the annular chamber 42, that is formed between the inner wall of the valve box and the outer wall of the valve member 20 and its flanges 30, 31. When the valve member 20 is in its forward position, shown in Fig. 2, this chamber 42 is in communication with a series of radial ports 43 leading through the valve 45 box and communicating at their outer ends with an annular chamber 44 formed between the valve box and the outer cylinder. This chamber 44 is in constant communication with the atmosphere through a suitable 50 number of ports 45 which open into a space covered by the spring clip 18, the latter having ports 46 therethrough to permit the escape of the fluid. When the valve member 20 is in its rear position shown in Fig. 1, 55 the chamber 42 is cut off from the exhaust ports 43 by the flange 31 on the valve, and a direct communication is established between said ports 43 and the piston chamber so as to permit the exhaust of the expended charge 60 of motive fluid from the rear end of the piston chamber upon the return stroke of the piston.

In order to prevent any trapping of air in the chamber in front of the valve flange 65 30, I provide a small vent 47, which com-

municates at one end with the exhaust chamber 44 and at its other end with the chamber 48 between the valve flanges 29 and 30. Another small port 49 leads from the main supply chamber 35 and terminates upon the 70 inner wall of the valve box in such position that it will be closed by the valve flange 30 when the valve member is in its forward position, shown in Fig. 2, but will be put into communication with the chamber 42 as soon 75 as the said valve member starts to move rearwardly.

The operation is as follows: When the thumb lever 34 in the handle 15 is pressed down the live motive fluid will be admitted 80 to the main supply chamber 35 and will act on the rear face of the flange 29, to move the valve forwardly into the position shown in Fig. 2. A charge of motive fluid is thus admitted through the inlet ports 39 into the 85 piston chamber, and the piston is driven forwardly thereby. The previous dead air which is in front of the piston, and in the storage chamber 21, escapes to the atmosphere 90 through the ports and passageways 40, 21, 41, 42, 43, 44, 45, and 46. As soon as the piston passes the escape ports 22 in the inner tube 11, a portion of the live charge 95 of motive fluid escapes therethrough past the check valve 23 and into the conduit 21 until the pressure in the said conduit is substantially equal to that in the piston chamber. This segregated charge passes through 100 the ports 41 into the chamber 42 and exerts a combined static and kinetic pressure 105 against the large flange 30 of the valve member 20, which overbalances the pressure in the chamber 37 upon the rear flange 29, and the valve member 20 will then be shifted to its rear position, as shown in Fig. 1. This 110 rearward movement uncovers the end of the port 49 and permits live motive fluid to flow from the main supply chamber 35 through said port 49 into the chamber 42 and thus assist in shifting the valve, and in maintaining it in its second position. The inlet ports 39 will now be cut off from the piston chamber and the exhaust ports 43 will be open. The live motive fluid which has passed into the storage chamber 21 will be prevented 115 from returning to the main piston chamber by the action of the check valve 23 and will pass through the ports 40 and exert a pressure upon the forward end of the piston to effect the return stroke of the latter.

As the piston moves rearwardly the pressure of the segregated charge in the storage chamber is progressively reduced by the expansion of the trapped motive fluid; and the force acting on the front and the rear 125 of the reciprocating member is thus progressively diminished, with a resultant slowing down of the velocity of its return movement. The motive fluid that is admitted to the chamber 42, through the passageway 49, 130

will, of course, pass into the chamber 21 (through the passageways 41), and will tend to aid and accelerate the rearward stroke of the piston; but the sizes of the passageways 49 and 41 are so proportioned that this effect will be relatively insignificant; and the restricted flow of high pressure air into the upper, or rear, end of the said storage chamber will not sensibly interfere with the continued expansion of the segregated charge and the progressive slowing down of the piston movement on its return stroke.

The relative volumes of the chamber 21 and the piston cylinder are preferably so proportioned that at the rear end of the piston stroke the pressure in the said connected chambers is not much above atmospheric. This drop in pressure reduces the force acting on the first valve flange 30 to such a point that it is no longer able to overcome the live air pressure on the rear of the smaller valve flange 29; and the valve 20 will be again shifted forwardly. If this reduction of pressure on the larger valve flange is not, in itself, sufficient to complete the desired movement of the valve, the said action will be supplemented by the closure of the small vent ports 38—by rearwardly moving piston—and the consequent rapid building up of the pressure in the restricted chamber space 37 to a point where it will be sufficient to force the said member to its forward position, shown in Fig. 2. The continued rearward movement of the piston under its own momentum is stopped and reversed by a cushion of fluid pocketed in the rear end of the piston chamber, and the above described cycle of operations is continued as long as the admission valve is kept open.

In the construction shown in Figs. 6-7 and 8 the main body, 10^a, of the hammer is provided with two inner tubes or sleeves 11^a and 50, the first of which constitutes the guide barrel, for the reciprocating piston member 12. This inside guide tube extends the entire length of the hammer and is held in position therein between the shoulder 51, at the inner end of the rivet set holder 13^a, and the soft packing washer 52 that may be inset either in the rear end of the handle sleeve 16^a or in the adjacent end of the valve box 19^a. The intermediate sleeve 50 is supported at its ends on annular collars 53, 54, which surround the adjacent parts of the inner piston tube 11^a, and the rear end of the said sleeve is also engaged by the forward extremity of the valve box member 19^a. The rear portion of the tube 11^a is ground and finished, on its exterior surface, to receive and guide the tubular distribution valve 20^a; and this valve is provided with two annular flanges 29^a and 30^a, which are fitted to slide smoothly in the respective chambers 37^a and 42^a of the valve box 19^a. This latter member is provided

with a series of radial passages 39^a which lead from the annular passage 35^a—between the rear end of the valve box and the interior of the handle head 16^a—to a chamber 55, in which the extreme rear end of the valve 20^a 70 is located; and the inner piston tube 11^a is provided with a corresponding series of radial ports, 39^b, which communicate with the chamber 55 when the valve is in the forward working stroke position shown in Fig. 6, 75 and which are closed when the valve is in the reverse return stroke position shown in Fig. 7. The valve box 19^a is also provided with two other series of radial passages, 43^a and 56; the first of which is in registry with 80 the exhaust ports 45^a in the main body 10^a of the hammer, and the second of which serve to connect the chamber 21^b—between the tubular members 10^a and 50—with the valve box chamber 42^a. The chamber 21^b 85 is in communication with the front end of the piston chamber through the ring of ports 40^a; and when the valve is in the position shown in Fig. 6 the air or other fluid can pass freely from that end of the inner tubular member through the ports 56, the chamber 42^a and the passageways 43^a and 45^a to the annular exhaust space under the spring clip deflector 18^a, and thence through the ports 46^a to the external atmosphere. The 90 body of the tubular valve 20^a is perforated with a series of radial ports 57, which are connected at their inner ends by a shallow annular groove 58 on the interior of the valve shell. A cooperating series of ports 100 60 are drilled through the piston guide tube 11^a, in such position that they register with the groove 59 when the distributing valve is in the rearward position shown in Fig. 7, and in such position the rear of the piston 105 chamber is, therefore, in free communication with the atmosphere through the ports 60—57, the chamber 42^a and the exhaust passageways, 43^a, 45^a and 46^a. The valve box 19^a of this construction is also provided with 110 two small live air supply passages 36^a and 49^a, which lead from the main supply chamber 35^a to the chambers 37^a and 42^a respectively. The first of these passages is always 115 open, but the forward end of the second one is closed by the external periphery of the valve flange 30^a when the valve is in its forward position (Fig. 6) and is only opened when the valve is shifted rearwardly to the 120 return stroke position (Fig. 7). The valve member itself is also provided with another restricted port 38^a which leads into an annular groove 38^b on the inner periphery of the valve shell; and the piston guide tube 11^a is drilled at 61 to form a vent opening 125 which is in registry with the groove 38^b when the valve is in the last described position.

The forward end of the piston guide tube 11^a is provided with a series of venturi shaped ports 22^a, the form of which is best 130

shown in Fig. 8. The inner enlarged ends of these ports open into the piston chamber at a point just back of the piston when the latter has completed its forward stroke and delivered its blow on the shank of the rivet set 14; and the outer contracted ends thereof open into the space 21^a, between the tubes 11^a and 50, which is in constant communication with the valve box chamber 42^a through one or more ports 41^a in the collar 54.

The operation of this last described construction is as follows: When compressed air is admitted to the supply chamber 35^a—through the handle passage 32^a—the valve 20^a is forced forward by the flow of the said air through the passageway 36^a into the chamber 37^a behind the rear valve flange 29^a. This opens the inlet ports 39^b and admits the live motive fluid to the rear end of the piston chamber to drive the piston forwardly against the rivet set 14. During this forward movement, the air in the front end of the piston chamber, and the chambers 21^a and 21^b, is allowed to escape to the atmosphere through the ports and passageways 56, 42^a, 43^a, 45^a and 46^a. When the piston, in its forward movement, reaches and covers the venturi shaped openings 22^a the inner storage chamber 21^a is cut off from communication with the external air; and when the rear end of the piston passes these openings a portion of the actuating charge of live motive fluid enters this chamber and passes through the ports 41^a into the chamber in front of the forward valve flange 30^a. The pressure thus created on the flange 30^a is in excess of the pressure exerted on the smaller rear flange 29^a, and the valve member 20^a is thrown rearwardly into the position shown in Fig. 7. This rearward movement of the valve closes the inlet ports 39^b, and puts the cylinder ports 60 in communication with the exhaust ports 57—43^a—45^a—and 46^a. It also shuts off communication between the main exhaust passageways and the ports 56 and puts the latter in communication with the chamber 21^b, thus allowing the live motive fluid in this chamber to fill the space 21^b and pass through the ports 40^a to the front end of the piston chamber. The sudden release of pressure on the back of the piston—by the opening of the exhaust from the rear end of the piston chamber—and the concurrent application of pressure to the front end thereof (by the flow of air through the ports 56 into the chamber 21^b) cooperates with the rebound of the reciprocating member from the end of the rivet set to initiate a quick reversal of the piston movement, that will cover the inner ends of the venturi ports 22^a before any large amount of the live motive fluid in the chamber 21^a can pass back through the restricted ends of the said ports and escape to the exhaust. The segregated portion of

the original live motive fluid charge which remains trapped in the storage chambers 21^a and 21^b gradually expands as the piston 12 moves rearwardly and thus exerts a progressively diminishing force on the reciprocating member; and the frictional resistance to the piston movement,—combined with the retardation by gravity when the hammer is operated in a vertical position—will produce a constant deceleration of velocity as the piston approaches the end of its return stroke. The aggregate volume of the chambers 21^a and 21^b is preferably so proportioned to the volume of the piston cylinder, that the pressure therein has been diminished to approximately that of the external air when the piston has completed its rearward movement; and the corresponding fall in pressure on the face of the valve flange 30^a permits the live air pressure on the rear flange 29^a to throw the valve forwardly, either just before, or just after, the piston has reached and covered the small vent ports 61. This forward movement of the valve again opens the live air ports 39^b, and the live motive fluid passing through these ports to the rear end of the piston chamber cooperates with the air that has been trapped and cushioned back of the piston—when the latter passes the exhaust openings 60—to quickly reverse the movement of the reciprocating member and drive it forward again.

In the two constructions above described the annular chamber, or chambers, between the outer, or main, barrel of the hammer and the inner piston guide tube serve both as a storage reserve for the segregation of a portion of the live motive fluid charge (for effecting the return movement of the piston) and also as passageways for the exhaust from the front end of the piston chamber during the working stroke. This is the form or type of construction which I prefer to employ because it eliminates all necessity for the drilling of long longitudinal passageways through the hammer barrel; and also because it permits of the easy renewal of the piston guide tube when the latter becomes worn or otherwise impaired by the rapid reciprocatory movement of the piston member. This construction is also considerably lighter and much less expensive than the usual solid barrel form of hammer; and it is also one that can be very easily and quickly assembled, or disassembled for repairs or for renewal of any injured parts.

The use of my present invention is not, however, dependent upon the employment of the double or multiple tube type of construction hereinbefore described. In Fig. 9 I have illustrated a modification of the ordinary solid barrel form of structure which is adapted to operate in accordance with my

new method of actuation. In this embodiment of my improvements I provide the lower, or forward, end of a solid hammer barrel 10^c with an enlarged head 65, which is rigidly secured thereto in any suitable manner and which is bored out to form a storage or segregation reservoir 21^c that communicates with the extreme front end of the piston chamber (just back of the rivet set shank 14) through the radial ports 40^c, and which is also in communication with that chamber through one or more valve controlled ports 22^c. The rear or handle end of the hammer barrel 10^c is bored out to receive a valve box construction similar to that shown in Figs. 1 and 2; and the chamber space 21^c is connected to the valve box passages 41 by means of one or more holes 66 that are drilled longitudinally through the solid side wall of this barrel. The check valve used in this construction, to control the port opening 22^c, consists of a small steel ball 67 which is held loosely in place between the coned or countersunk end of this opening and the adjacent face of the shoulder 67. This same form of check valve may be used in the constructions shown in Figs. 1 to 8; in which case the ball element is held in place between the outwardly flared end of the port 22 and the adjacent face of the hammer barrel 10 (as shown in Fig. 10) or between a corresponding shaped port 22^a and the inner face of the intermediate tube 50.

The mode of operation of the construction illustrated in Figs. 9 and 10 is the same as that which generically characterizes the previously described embodiments of my invention; and is specifically the same as that of the structure shown in Figs. 1 to 5. When the piston 12 reaches the position shown in Fig. 9 the live motive fluid in the rear of the reciprocating member passes through the port (or ports) 22^c and fills the reservoir 21^c and the passageway 66, thereby moving the distribution valve to its rearward position in the manner previously explained. This closes the rear end of the passage 66 and opens the rear end of the piston chamber to the exhaust; and the resultant drop in pressure back of the piston sucks the ball valve 67 against its seat and traps a segregated mass of live motive fluid in the reservoir 21^c. This segregated charge passes through the ports 40 and effects the return of the piston by its continued expansion; and the continued drop in pressure thereby produced ultimately reduces the force acting on the front flange of the distribution valve to such a degree that the said member is moved forwardly, and one complete cycle of operations is thus concluded.

The advantages and improved results that are secured by the use of my invention in fluid actuated pressure tools will now be appreciated by those skilled in the art. Brief-

ly summarized, some of the more important functional and result-attaining features that characterize my present improvements are as follows:

First; the segregation of a portion of the working charge of high pressure motive fluid, near the end of the forward stroke, in a storage reservoir that is in direct and constant communication with the front of the piston chamber, results in the practically instantaneous initiation of the return movement of the reciprocating member after it delivers its power blow on the working tool; and this effects a saving of time that results in a substantial increase in the number of strokes per minute (for a given motive fluid pressure) and a corresponding augmentation of the driving power of the hammer.

Second; the return of the reciprocating member by the expansion of a segregated and confined charge of high pressure fluid, produces a geometrical reduction in the accelerating force acting on the rearwardly moving piston, which results in a very marked decrease in the velocity of that member as it nears the rear end of its stroke. This, in turn, makes it possible to more quickly and easily arrest and reverse the movement of the piston at the beginning of the next power stroke; and to thus effect a further saving in time with a resultant increase in working speed. The progressive slowing down of the reciprocating member during its return movement also makes it possible to reduce the "cushioning" space at the rear end of the piston chamber—by locating the main admission and exhaust ports closer to that end—and thus substantially increase the possible effective length of power stroke for a given length of hammer barrel.

Third; the progressive decrease in the actuating pressure on the front end of the piston and the marked slowing down or deceleration of that member before the cushioning action begins—which results in greatly reducing the final compressive pressure produced by that action eliminates, or very greatly reduces, the "back kick" or recoil of the hammer against the hand of the workman, and thus enables him to more effectively hold it in driving position, and operate it with less muscular strain and fatigue.

Fourth; the segregation of a portion of the working charge of live motive fluid during the power stroke of the hammer, and the utilization of that segregated portion to return the piston by expansion, results in an increased economy and efficiency in operation; not only because of the saving in the volume of compressed air used for each reciprocation, but also because of the cooling effect, produced by the expansion of the working charge in the hammer barrel—particularly on the rivet set end thereof—which

tends to keep the operating parts in better condition for long continued use.

Fifth; the decrease in the final pressure in the piston chamber on the return stroke, 5 reduces the quantity of exhaust from the front end of that chamber during the succeeding forward movement of the reciprocating member; and to that extent reduces the back pressure on the piston, and the 10 accompanying losses by friction, etc., in the outlet passages. This tends to further increase the velocity and the resultant kinetic energy of the piston on its impact stroke; and the effect under consideration is of particular 15 advantage and importance when the exhaust ports become clogged or obstructed with oil or dirt—as not infrequently happens in the use of these tools.

Sixth; my improved mode of operation— 20 of actuating the piston in both directions by a single working charge of air, and effecting a deceleration or a progressive slowing down of the piston movement on the return stroke—enables me to simplify the design 25 and construction of the mechanical organization, and thereby reduce the first cost of manufacture. It also makes it possible to reduce the diameter and length of the 30 tool—as compared with those heretofore in use—and to thus substantially decrease the weight and bulk of a hammer of given rated capacity or driving power; thereby facilitating the manipulation of the tool 35 and enabling the operator to use it in very cramped and confined quarters.

Seventh; the increased facility and ease 40 of manipulation,—due in part to the lighter weight and in part to the decrease in vibration and recoil shock—the augmented driving power (resulting from the greater number of strokes per minute); and the higher degree of economy and efficiency in the use 45 of motive fluid; all mutually cooperate to very substantially increase the working capacity of fluid actuated pressure tools 50 which are constructed and operated in accordance with my present invention; and to correspondingly decrease both the first cost and the continued expense of maintenance 55 of the power plant and the battery equipment required to perform a given amount of work.

While I have in the foregoing description 60 gone into considerable detail relative to the particular constructions of the exemplary tools shown in the drawings, it should be understood that this minute description has been given for the purpose of lucidity only 65 and is not in any way to be construed as a limitation of my invention. The various tools shown and described are only a few of many structures which might be employed in practicing my invention; and it is only because the present improvements 70 are especially advantageous in connection

with pneumatic hammers that I have shown and described them as so applied. As indicated above many different arrangements of the storage chamber and the piston chamber, and various forms of control and distribution valves and valve boxes, may be used in connection with the present development; and these and other details of construction may be varied widely without departing from the scope of my invention. 75

It should also be noted that in my co-pending application Serial No. 483,794, filed July 11, 1921, I have claimed the specific structural or mechanical relation between the outer and inner tubular members and the 80 valve-box herein illustrated, as well as the structural relation between those elements and the handle-portion of the tool and the specific means employed for locking those elements together and guarding the locking 85 means; consequently such structural details are not claimed herein.

I claim as my invention:

1. A method of reciprocating pistons of 90 pneumatic tools, which comprises the forward movement of the piston by the application of a live air charge to the rear of the piston and the concurrent expulsion of fluid from the front thereof, the mixing of a portion of the live air charge with the expelled 95 fluid and the utilization of the increased pressure thus produced in the mixture to initiate the rearward stroke of the piston.

2. The method of reciprocating the piston 100 of pneumatic tools which comprises the forward actuation of the piston by a charge of motive fluid applied to the rear of the piston, the concurrent expulsion of fluid from the front thereof, the increase in pressure in the escaping fluid by mixing it with a portion 105 of the charge of fluid from the rear of the piston, and the utilization of the increased pressure thus produced to initiate the rearward stroke of the piston.

3. The method of reciprocating the piston 110 of pneumatic tools which comprises the forward actuation of the piston by motive fluid applied to the rear of the piston, the concurrent expulsion of fluid from the front thereof, the increase in pressure in the fluid so 115 expelled by mixing it with a portion of the charge of motive fluid from the rear of the piston, and the utilization of the increased pressure thus produced to concurrently confine the mixed charge and utilize it in the initiation of the rearward movement of the piston.

4. The method of operating fluid driven 120 percussion tools which comprises the forward actuation of a reciprocating piston member by a charge of high pressure motive fluid applied to the rear of the piston, the concurrent expulsion of fluid from the front thereof, the mixing of a portion of the high pressure fluid charge with the fluid so expelled 125 130

and the utilization of the mixed charge in concurrently actuating the charge admission valve and in initiating the rearward movement of the reciprocating piston.

5. The method of operating fluid driven percussion tools which comprises the forward actuation of the reciprocating piston member by a charge of high pressure motive fluid applied to the rear of the piston, the concurrent expulsion of fluid from the front of the piston chamber, the increase in velocity of the fluid so expelled by mixing therewith a portion of high pressure fluid charge and the utilization of the increased velocity thus produced in trapping the mixed fluid in front of the piston.

6. The method of reciprocating a valve controlled detached impact piston of a fluid actuated tool having a charge admission valve, and of actuating the valve, which comprises the forward actuation of the piston by a charge of high pressure motive fluid applied to the rear of the piston through the valve, the concurrent expulsion of fluid from the front of the piston, the mixing of a portion of high pressure fluid, from the rear of the piston with fluid so expelled and the utilization of the mixed charge in concurrently actuating the valve to trap the mixed charge and in initiating rearward movement of the piston.

7. The combination with the cylinder and detached piston of a fluid-actuated impact tool, of an annular chamber surrounding the cylinder and communicating freely therewith at its forward end; a valve mechanism at the rear end of the cylinder for controlling admission of the motive fluid behind the piston to produce the working stroke and for also controlling the venting of the cylinder in front of the piston through said chamber and for venting of the cylinder behind the piston; means for entrapping fluid from the cylinder in said chamber during the working stroke; means for admitting fluid so entrapped to shift the valve to cause return of the piston by such fluid; and means controlled by the returning piston for causing reverse shifting of the valve to initiate another working stroke.

8. A method of reciprocating pistons of pneumatic tools, which comprises the forward movement of the piston by the application of a live air charge to the rear of the piston and the concurrent expulsion of fluid from the front thereof, the mixing of a portion of the live air charge with the expelled fluid and the concurrent trapping of the mixture and the utilization of the trapped mixture in initiating and continuing the rearward stroke of the piston.

9. In combination in a pneumatic hammer, a cylinder, a piston operating therein, an exhaust passage in open and free communication with the forward end of the cylinder,

means intermediate the ends of the cylinder for delivering fluid under pressure from the cylinder to the passage, and a valve mechanism actuated by fluid within the exhaust passage for controlling the delivery end of the exhaust passage.

10. In combination in a pneumatic hammer, a cylinder, a free piston operating therein, an exhaust passage in open and free communication with the forward end of the cylinder, means intermediate the ends of the cylinder for delivering fluid under pressure from the cylinder to the passage and a valve mechanism for controlling the delivery and discharge of fluid to and from the rear end of the cylinder and the discharge of fluid from the passage, responsive in operation to the action of the fluid within the passage.

11. In combination in a pneumatic tool, a working cylinder having a fluid inlet and a fluid outlet port at the rear end thereof, a free piston operating in said cylinder, a valve casing having a fluid discharge port, a chamber in free communication with the forward end of said cylinder, means for delivering fluid under pressure from said cylinder to said chamber, and a valve located in said valve casing and responsive to pressure within said chamber for controlling the delivery and discharge of air from said cylinder through said inlet and outlet ports and communication between said chamber and said discharge port.

12. In combination in a pneumatic tool, a cylinder, a free piston operating therein, a chamber extending longitudinally of said cylinder and in open and free communication with the forward end thereof, a valve located at the rear end of said piston and responsive to fluid pressure within said chamber for controlling the delivery of motive fluid to the rear end of the cylinder, the discharge of fluid from the rear end of the cylinder and the discharge of fluid from said chamber, and means for admitting high pressure fluid from said cylinder to said chamber to shift said valve thereby cutting off the discharge of fluid from said chamber and the delivery of high pressure fluid to said cylinder.

13. In combination in a pneumatic tool, a working cylinder having a fluid inlet port and a fluid outlet port at its rear end, a free piston within said cylinder, a chamber extending longitudinally of said cylinder and in free communication with the forward end thereof, a valve casing having a fluid discharge port, a valve within said casing and responsive to fluid pressure within said chamber for controlling said fluid inlet port, communication between said fluid outlet port and said discharge port and communication between said chamber and said discharge port, and means for delivering high pressure fluid from said cylinder to said chamber.

to actuate said valve to close communication between said chamber and said exhaust port and to initiate and continue the rearward movement of said piston.

- 5 14. In combination in a pneumatic tool, a cylinder having fluid inlet and exhaust ports at the rear end thereof, a free piston within said cylinder, a chamber in open communication with the forward end of said cylinder, 10 a valve subjected to pressure within said chamber, and controlling said ports and communication between said chamber and the atmosphere, means for admitting high pressure fluid from said cylinder to said chamber, 15 to move said valve to close said chamber and said inlet port and to open said exhaust port, and means controlled by said piston for

occasioning a movement of said valve to open said chamber, said inlet port and to close said exhaust port. 20

15. In combination in a pneumatic tool, a working cylinder having a fluid inlet port and a fluid outlet port at the rear end thereof, a free piston operating within said cylinder, an exhaust passage for the forward end of said cylinder, a valve for controlling the discharge of fluid from said passage and the delivery of fluid through said inlet and outlet ports, and means for delivering high pressure fluid from said cylinder behind 25 said piston to said exhaust passage.

In testimony whereof, I have hereunto set my hand.

FRANK L. O. WADSWORTH.
